UNITED STATES PATENT OFFICE.

JEREMIAH STOKES, JR., OF SALT LAKE CITY, UTAH.

STOVEPIPE-ANCHOR.

1,174,196.

Specification of Letters Patent.

Patented Mar. 7, 1916.

Application filed February 18, 1915. Serial No. 9,125.

To all whom it may concern:

Be it known that I, JEREMIAH STOKES, Jr., a citizen of the United States, residing at Salt Lake City, in the county of Salt Lake and State of Utah, have invented certain new and useful Improvements in Stovepipe-Anchors; and I do declare the following to be a full, clear, and exact description of the invention, such as will enable others skilled in the art to which it appertains to make and use the same.

My invention relates to new and useful improvements in stove pipe anchors and has for its object to provide a device of this character which may be very simply and inexpensively manufactured and marketed, yet one which, when applied to use, will be very efficient in operation and will not only anchor the stove pipe, but will hold the usual thimble, receiving the pipe, against movement.

With this end in view, the invention resides in certain novel features of construction and combination hereinafter described and claimed and shown in the drawings wherein:

Figure 1 is a vertical section of a chimney and a stove pipe projecting into the same, showing the application of the invention to use; Fig. 2 is a horizontal section as seen along the plane indicated by the line 2—2 of Fig. 1; and Fig. 3 is a perspective view of the main portion of the anchoring device.

In this drawing, constituting a part of the application, C designates an upright flue or chimney having an opening O in one of its side walls, said opening being provided with the usual thimble T into which the pipe P extends.

Disposed within the thimble T, is the longitudinally extending shank 1 of a hook, the front end of this shank being provided with an eye 2, while its rear end is bent downwardly and outwardly as seen at 3 to provide a U-shaped bill 4 which is interposed between the lower side of the thimble T and the wall of the opening O. The free end of the bill 4 is bent upon itself and is continued inwardly and laterally to provide a stop 5, the free end of this stop being, in turn, bent at right angles and extended inwardly into parallel relation with the shank 1 and bill 4, thus forming an attaching foot 6. Adjustably secured to this foot by any

suitable means, such for instance as a thumb screw 7, is the forward end of a longitudinally extending bracing strip 8, the other end of said strip being preferably sharpened as seen at 9 for engagement with the wall of the chimney opposite that provided with the opening O.

10 designates one end of a wire 11, said end being bent into the form of a hook which receives the front end of the thimble T, the wire 11 being continued inwardly from said hook through the eye 2, and being then bent upon itself and extended outwardly. The remaining end 12 of said wire 11 is then bent to form an eye which receives a suitably shaped hook 14 carried by the rear end of an anchoring wire 15, the body portion of the latter being disposed in the pipe P, while its remaining free end is projected outwardly through an opening 16 therein and is wound upon a cylindrical stem 17.

The stem 17 is revolvably mounted in an appropriate bearing plate 18 which is disposed within and secured to the pipe P as clearly shown in Figs. 1 and 2, the outer end of said stem having operating wings 19, while the inner end thereof is equipped with a ratchet 20 with which a spring pressed pawl 21 coacts, the latter being pivoted to the plate 18. By this construction, it will be seen that rotation of the stem 17 in the proper direction will wind the wire 15 thereon, thus having a tendency to pull the stop 5 into direct contact with the wall of the chimney, and force the thimble T inwardly into contact with the bend 3, which now limits the inward movement of said thimble. During this operation, it will be evident that the inner end of the pipe P is likewise forcibly projected into the thimble T, that its inward movement is limited by contact with the shank 1, and that the inward movement of all parts is prevented by the stop strip 8, it being therefore seen that the invention, although very simple and inexpensive, will be extremely efficient in operation.

I claim:

1. The combination with a chimney having an opening in one wall, and a thimble in said opening; of a hook shank disposed longitudinally in the thimble and having a U-shaped bill receiving the inner end thereof, a stop projecting laterally from said

bill and abutting the inner side of the aforesaid wall, an additional stop extending longitudinally from the aforesaid stop and bearing against the opposite wall of the chimney, and a pipe anchoring element leading outwardly from the aforesaid hook shank.

2. The combination with a flue having an opening in one wall, and a thimble in said opening, of an anchoring device including a stop member contacting with the inner side of the aforesaid wall, an additional stop member contacting with the opposite wall of the flue, and a guide eye disposed in the thimble, an anchoring wire, and a stop formed on one end thereof, said stop being disposed in contact with the front end of the thimble, and a wire being extended inwardly therefrom through the guide eye and being then continued outwardly.

3. The combination with a flue having an opening in one wall, and a thimble in said opening, of a hook shank disposed longitudinally in the thimble and having at its outer end an eye, and at its inner end a U-shaped hook receiving the inner end of the thimble, a stop projecting laterally from said hook and abutting the inner side of the aforesaid wall, an additional stop projecting longitudinally from the aforesaid stop and abutting the opposite wall of the flue, and a wire having a hook at one end receiving the outer end of the thimble, said wire being extended inwardly through the

eye and being then bent upon itself and continued outwardly.

4. An anchoring device comprising a strip of metal having a perforated end, said strip being bent substantially upon itself to form a U-shaped hook, the unperforated end of the latter being bent upon itself and then bent laterally to form a stop member, and the latter being bent at right angles to provide an attaching foot, combined with a bracing strip adjustably secured to said foot, and a fastening element connected to the perforated end and adapted for connection with a stove pipe.

5. The combination with a chimney having an opening, a thimble in said opening, a stove pipe projecting into said thimble, and stop means limiting the inward movement of said pipe; of a wire having a hook at one end receiving the outer end of the thimble, said wire being extended inwardly and engaged with said stop means, being then bent upon itself and continued outwardly, and terminating in an eye, and a stove pipe fastening element connected with said eye.

In testimony whereof I have hereunto set my hand in presence of two subscribing witnesses.

JEREMIAH STOKES, JR.
